Primary Examiner — Rhea Shields(74) *Attorney, Agent, or Firm* — Yakov Sidorin; Quarles & Brady LLP(57) **CLAIM**

The ornamental design for a tonometer tip housing, as shown and described.

DESCRIPTION

FIG. 1 is a perspective view of the design;
FIG. 2 is another perspective view of the design;
FIG. 3 is a first side elevational view thereof;
FIG. 4 is a second side elevational view thereof;
FIG. 5 is a third side elevational view thereof;
FIG. 6 is a fourth side elevational view thereof;
FIG. 7 is a top plan view thereof; and,
FIG. 8 is a bottom plan view thereof.
